CLAIM

The ornamental design for a keyboard enclosure for a personal computer or the like, as shown and described.

DESCRIPTION

FIG. 1 is an isometric view of a keyboard enclosure for a personal computer or the like, showing our new design.

FIG. 2 is a side view thereof, showing the legs in their extended position.

FIG. 3 is a bottom view thereof, showing the legs in their retracted position.

The undisclosed side of the enclosure is identical to that shown in FIGS. 1 and 2, although the keys per se differ as indicated in FIG. 1.
